UNITED STATES PATENT OFFICE.

BENJAMIN URQUHART, OF PLAINFIELD, NEW JERSEY.

REGULATED-CONTACT PUSH-BUTTON.

1,059,013.

Specification of Letters Patent. Patented Apr. 15, 1913.

Application filed October 5, 1909. Serial No. 521,060.

To all whom it may concern:

Be it known that I, BENJAMIN URQUHART, a citizen of the United States of America, residing at Plainfield, in the county of Union and State of New Jersey, have invented certain new and useful Improvements in Regulated-Contact Push-Buttons, of which the following is a specification.

My invention relates to electrical switches or push buttons for use in electrical circuits in connection with call bells, buzzers, signals and the like, and has for its object the regulation of the duration of contact regardless of the duration of pressure thereon and the consequent prevention of the prolonged sounding of such signals and the waste of electric energy due to unnecessarily prolonged contact; also to guard against injury to the contact points by violent or careless operation; and the simplification of construction in devices of this character.

The features of the invention by which such results are attained by me are the interposition between the actuated and the actuating parts of the device, of an elastic though positive pneumatic cushion and means to regulate the same whereby the duration of the contact can be accurately predetermined.

The invention as particularly set out in the accompanying claims, will be readily understood from the following detailed description taken in connection with the accompanying illustrative drawings, in which—

Figure 1 is a longitudinal section of one form of the device suited especially for use of patients in hospitals and the like; Fig. 2 is a similar view of another embodiment adapted for door bells, buzzers, and like signals permanently placed; and Fig. 3 is a similar view of a form possessing great simplicity and a minimum number of parts for use in the same connection.

Referring to Fig. 1 of the drawing, the cylindrical box 1 has at one end an overhanging flange 2 and forms a cylinder for the cup shaped primary or actuating piston 3 which is provided with an operating button 4 extending through the opening formed by the flange 2. A sleeve 5 having a flanged base 6 is threaded into the lower open end of the box 1 in opposition to the primary piston 3. Within this sleeve as a cylinder is mounted a secondary or contact making

piston 7, provided with a contact 8 and a small vent 9 controlled by a screw valve 10. An insulation plate 11 overlies the flanged base 6 and closes the bottom of the sleeve 5. This plate carries a stationary electrode 12 arranged in line with the contact 8 and connected electrically with one terminal 13 of the electric circuit of which the other terminal 14 is connected to the base 6. A spring 15 is arranged in the confined space between the two pistons 3 and 7, bearing above on the piston 3 and below on the upper edge of the sleeve 5. The end 15^a of this spring may extend within beyond the sleeve to form a stop to limit the upward movement of the secondary piston 7, or other suitable stop may be provided. A weak spring 16 arranged beneath the piston 7 and bearing against said piston on the one hand and on the other against the insulation plate 11 tends to normally hold the contact 8 and the electrode 12 separated.

The operation is as follows: When the button 4 is pressed, the spring 15 is placed under compression and the body of air confined within the chamber 17 formed between the two pistons is compressed, with the result that the secondary piston 7 is forced outward against its spring 16 until the contact 8 strikes the electrode 12 and closes the circuit, sounding the call. When the button is released, the spring 15 returns the piston 3, relieving the confined air or pressure and permitting the piston 7, under the influence of its spring 16, to rise, breaking the circuit through the contact and electrode. If the push button is not released but through accident or design is held down, the air will escape from the chamber 17 through the vent 9 to the chamber 18 formed below the piston 7, the equalization between the two chambers taking place more or less quickly according to the adjustment of the valve 10 controlling the vent. The spring 16 will then lift the piston 7 and break the circuit in a predetermined length of time after the contact was made.

In Fig. 2 is shown an embodiment of the invention adapted particularly to the operation of door bells, buzzers in offices and the like. Here the parts are the same except as to shape and as to the substitution for the spring 15 of a spring 15^a arranged above instead of below the piston 3. The operation is precisely the same.

1. In an electric switch, the combination shown wherein the functions of the two pistons 3 and 7 are combined in the upper side 3^a and the lower side 7^a respectively of a hollow elastic body such as a ball 19. The inherent elasticity of the rubber body tending to separate the sides 3^a and 7^a, takes the place of the spring 15. On the lower face of the ball 19 is fixed a contact plate 20 having a central contact 21, arranged in line with the electrode 12. The spring 16, in this case, bears above on the contact plate 20 and, below on the base 6, making an electrical connection between the two. The operation is precisely the same as in the other embodiments heretofore described.

Having thus fully described my invention and the manner of its operation, what I claim as new and desire to secure by Letters Patent is;

20 1. In an electric switch, the combination of a cylinder, a primary and a secondary piston arranged therein and inclosing an intermediate air chamber, a valve controlling a vent from the air chamber, a normally open electric circuit connected to the secondary piston at one terminal and with the other terminal arranged in the path of the said piston, the primary piston provided with means to operate the same.

25 2. In an electric switch, the combination of a cylinder, a primary and a secondary piston arranged therein and inclosing an intermediate air chamber with a regulable vent, one terminal of a normally open electric circuit connected to the secondary piston and the other terminal with an electrode arranged in the path of the said piston, the primary piston provided with a push button to operate the same.

30 3. In an electric switch, the combination of a cylinder, a primary and a secondary piston arranged therein and inclosing an intermediate air chamber, a valve controlling a vent from the air chamber a normally open electric circuit one terminal of which is connected to the secondary piston, an electrode arranged in the path of the said piston and connected to the other terminal of the circuit, a spring tending to hold the pistons apart, and the primary piston provided with means to force the same toward the secondary piston.

35 4. In an electric switch, the combination of a cylinder, a primary and a secondary piston arranged therein and inclosing an intermediate air chamber with a regulable vent, one terminal of an electric circuit connected to the secondary piston, an electrode arranged in the path of the said piston and connected to the other terminal of the circuit, a spring holding the primary piston away from the secondary piston, and a second spring holding the secondary piston away from the electrode, the primary pis-

ton provided with a push button to force the same toward the secondary piston.

5. In an electric switch, a body having relatively movable walls forming therebetween an imperfectly sealed air chamber, an electric circuit having one terminal carried by one of the movable walls and the second terminal arranged in the path of movement of the first terminal, a push button arranged to bear upon a movable wall other than that carrying the first terminal to move the same toward but short of contact with the other wall carrying the first terminal to compress the contained air and thus transmit such movement to the wall carrying the first terminal whereby to close the circuit, the walls of the body tending to reassume their original position when the normal pressure of air therein is restored by release of the button or leakage therefrom of the compressed air, whereby the duration of contact of the terminals is unaffected by prolonged depression of the button.

20 6. In an electric switch, the combination of a cylinder, a piston therein, a movable element within the cylinder in front of the piston, a body of air imperfectly sealed between the piston and movable element, a normally open electric circuit having one terminal carried by the movable element and the other arranged in the path of forward movement thereof, a push button to actuate the piston, and means tending to restore the movable element to its original position, the operation of said means controlled by the gradual escape of the air from between the piston and movable element.

25 7. In an electric switch, the combination of a cylinder forming an air chamber, a piston therein, a push button carried by said piston, a movable element in said cylinder adapted to be pushed by the compression of air in said cylinder consequent upon depressing said button, an electric circuit having one terminal carried by said movable element and the other terminal in the path of movement thereof, and means automatically acting to separate said terminals when the air previously compressed in said cylinder is exhausted, whereby the continued depression of said button is ineffective to maintain said terminals in contact.

30 8. In an electric switch, a body including relatively movable elements forming therebetween an imperfectly sealed air chamber, an electric circuit having one terminal carried by one of the movable elements and the other terminal arranged in the path of movement of the first terminal, actuating means to move an element other than the terminal-carrying element toward the terminal-carrying element to compress the contained air, the compressed air serving to transmit such movement to the last named element and to the terminal carried thereby

to close the circuit, the terminal-carrying element tending to reassume its original position when the normal pressure of air therein is restored by the release of the actuating means or leakage of the compressed air, whereby the duration of contact is limited in extent.

In testimony whereof I affix my signature in presence of two witnesses.
